UNITED STATES PATENT OFFICE.

ENRICO FEROLDI, OF TURIN, ITALY.

CARBURETER FOR EXPLOSION-ENGINES.

1,307,396.

Specification of Letters Patent. Patented June 24, 1919.

Original application filed February 28, 1918, Serial No. 219,556. Divided and this application filed December 14, 1918. Serial No. 266,757.

To all whom it may concern:

Be it known that I, ENRICO FEROLDI, subject of the King of Italy, and resident of Turin, Italy, have invented certain new and 5 useful Improvements in Carbureters for Explosion-Engines, of which the following is a specification, this application being a division of U. S. application N. 219,556, filed Febr. 28, 1918, and the subject-matter of this 10 application having been first described in said U. S. application N. 219,556.

This invention relates to explosion engines provided with two or more carbureters and has for its object an arrangement by which 15 the supply of fuel to said carbureters is controlled according to requirements also in the case the float of one or more of said carbureters comes out of operation, by way of example, because it is holed or damaged in any 20 manner, this causing the same to become full and the operation of the carbureter not satisfactory.

As it is known, in such a case, in the usual constructions of carbureters, the carbureter 25 or carbureters fed by the chamber or chambers having their respective floats out of operation, is or are liable to flooding as the fuel fed thereto under these circumstances is in excess with respect to requirements.

According to this invention the float chamber of the two or more carbureters feeding the engine cylinders are interconnected by means of a duct opening in each of said chambers above the level the fuel must reach 35 into the same for securing the proper supply to the carbureter nozzles.

The annexed drawing shows by way of example two constructions of carbureters according to the invention and Figure 1 is 40 the section of an arrangement comprising two carbureters, the section being made on the central axes of the float chambers; Fig. 2 is the like section of another arrangement in which the float chambers of the two carbureters are integral with each other.

As shown in Fig. 1, both carbureters I and II are provided with a float chamber 1 into which the fuel is supplied through connecting piece 2 connected with the pipe leading 50 to the main fuel tank not shown, the fuel being fed as usual from said chamber 1 to the carbureter nozzle through passage 3.

Inside each chamber 1 is arranged a float 4 which operates arms 5 pivoted at 6 on the 55 cover of the chamber 1 and intended to actu-

ate the needle or pin 7 which is adapted to shut by its head the supply of fuel to chamber 1 when the same fuel has reached the desired level into said chamber 1.

According to this invention the float 60 chambers 1 of the carbureters feeding the engine are caused to communicate with each other by means of orifices 12 opening above the required constant level of the fuel in said chambers, said orifices being interconnected 65 by means of a passage 13.

By such an arrangement should either of floats 4 become damaged and filled in with fuel so as to be sunk into the fuel and prevented from properly operating to control 70 the fuel inlet into its chamber 1, the excess of fuel coming into this chamber overflows through orifices 12 and passage 13 into the float chamber 1 of the other carbureter, the direct supply of fuel from main tank into 75 this chamber through connecting piece 2 and pipe leading thereto being reduced and prevented, if required, by the needle 7 operated by the float 4 of this chamber 1.

Under the circumstances which are generally found in practice, the inlet orifice of the fuel into chamber 1 is hardly sufficient to feed fuel to two carbureters, so that in the above described case in which the float of one of the carbureters is sunk and out of 80 operation, the supply of fuel to both carbureters is quite regular and satisfactory for the normal running of the engine, this supply being, if required, properly controlled by the operation of the float of the other 85 carbureter.

Obviously the same result may be obtained in the case of a plurality of carbureters by interconnecting their float chambers by means of passages opening into the same 95 above the constant level of fuel therein; as above described, the excess of fuel supplied into the float chamber of any carbureter having its float out of operation overflows into one or more of the other ones the direct 100 supply to these latter ones from the main tank being controlled by their respective floats and needles.

Further, according to this invention, any possibility may be prevented that the fuel 105 supplied to one of the float chambers, when the float thereof is out of operation, may be in excess with respect to the fuel required for feeding both or all carbureters, this fact being liable to produce flooding of all carbu- 110

reters notwithstanding their direct communication with main tank is cut off by the operation of their respective float with exception of the chamber having its float sunk.

5 To this end may be used any arrangement adapted to limit rising of the needles 7 operated by said floats and controlling the fuel inlet into chambers 1.

A construction of such an arrangement is 10 shown by way of example on Fig. 1; in this construction, on the bottom of each chamber 1 is provided a sleeve 9 having holes 10 and intended to support and stop the float 4 at a given distance from said bottom when 15 said float moves to come into contact with said bottom for any reason.

The needle 7 which, as usually, passes through the central hole of the float, is correspondingly provided with an enlarged 20 head 8 adapted to come into contact with the lower surface of the float when this latter is supported by sleeve 9, so that said needle is stopped after it has been raised to a given extent which may be predetermined according 25 to circumstances in such a way as to reduce the amount of fuel supply into chamber 1.

The same result may also be obtained by 30 means of a cap 11 mounted on the cover of the float chamber 1, this cap encircling the upper head of needle 7 and limiting its upward stroke, independently of the control of the respective float.

In any case the operation of the device is 35 identical with that above described and does not require further specification.

Fig. 2 shows a construction of the arrangement according to this invention in which twin carbureters have their float chambers 40 1-1 close to or integral with each other and interconnected by a port 13 opening into said chambers 1 above the normal level of fuel therein; the fuel is fed into said chambers from a lower common passage 2' connected with the main fuel tank not shown. The operation is identical with that described in connection with Fig. 1.

By the arrangement according to this invention is prevented in any case that the 50 carbureter or carbureters have their respective floats out of operation the liability of flooding by way of the excess of fuel supplied thereto is prevented.

What I claim as my invention and desire 55 to secure by United States Letters Patent is:

1. In an explosion engine, a plurality of

carbureters feeding the engine cylinders, each carbureter having a float chamber feeding its nozzle and connected with the main fuel tank, means for controlling the fuel 60 inlet into each constant level chamber, the wall of each of said chambers having an opening above the fuel constant level therein, and means interconnecting said openings to cause the excess of fuel into any of said float 65 chambers, when the respective controlling means are out of operation, to overflow into other ones.

2. In an explosion engine, a plurality of carbureters feeding the engine cylinders, each 70 carbureter having a float chamber feeding its nozzle and connected with the main fuel tank, means for controlling the fuel inlet into each float chamber, a float inside each chamber to operate said controlling means, the 75 wall of each float chamber having an opening above the fuel constant level therein, and means interconnecting said openings to cause the excess fuel into any of said float 80 chambers when the respective float and controlling means are out of operation, to overflow into other ones.

3. In an explosion engine, two carbureters feeding the engine cylinders, twin float 85 chambers each feeding a nozzle and connected with the main fuel tank, means for controlling the fuel inlet into each float chamber, a float inside each chamber to operate said controlling means, a passage interconnecting said float chambers above the constant fuel level therein for causing the excess fuel inside either of them, when the respective float and controlling means are out 90 of operation, to overflow into other ones.

4. In an explosion engine, a plurality of 95 carbureters, feeding the engine cylinders, each carbureter having a float chamber feeding its nozzle and connected with the main fuel tank, a valve for controlling the fuel inlet into each chamber, a float inside each 100 chamber to operate said valve, the wall of each float chamber having an opening above the fuel constant level therein, means interconnecting said openings to cause the excess fuel inside any of said chambers, when the 105 respective float and valve are out of operation, to overflow into other ones, and means in each float chamber for limiting the rising of the respective valve.

Signed at Turin, Italy, this 13th day of 110 November, A. D. 1918.

ENRICO FEROLDI.
